US00D875110S

(12) **United States Design Patent** (10) Patent No.: **US D875,110 S**
(45) Date of Patent: ** Feb. 11, 2020

(54) **DISPLAY SCREEN OR PORTION THEREOF
WITH GRAPHICAL USER INTERFACE**

(71) Applicant: **Johnson Controls Technology
Company**, Auburn Hills, MI (US)

(72) Inventors: **Daniel J. Spors**, West Bend, WI (US);
Michael F. Kornacki, Oak Creek, WI (US); **Steven J. Grobschmidt**, Glendale, WI (US); **Vineet Sinha**, Brookfield, WI (US); **Mark Thoni**, Pewaukee, WI (US); **Scott Holland**, Brookfield, WI (US); **Hyunchul Kim**, Chicago, IL (US); **Michael Lemon**, Chicago, IL (US); **Nikhil Mathew**, Vernon Hills, IL (US); **Holly Prouty**, Chicago, IL (US)

(73) Assignee: **Johnson Controls Technology
Company**, Auburn Hills, MI (US)

(**) Term: **15 Years**

(21) Appl. No.: **29/657,047**

(22) Filed: **Jul. 18, 2018**

Related U.S. Application Data

(63) Continuation of application No. 29/602,691, filed on May 2, 2017, now Pat. No. Des. 828,816, which is a continuation-in-part of application No. 29/590,757, filed on Jan. 12, 2017, now Pat. No. Des. 844,570.

CLAIM

We claim the ornamental design for a display screen or portion thereof with graphical user interface, as shown and described.

DESCRIPTION

FIG. 1 is a front view of a display screen or portion thereof with a graphical user interface according to one embodiment; and,

FIG. 2 is a front view of a display screen or portion thereof with a graphical user interface according to another embodiment.

The outermost broken lines in the figures illustrate a display screen or portion thereof and form no part of the claimed design. The other broken lines in the figures illustrate portions of the graphical user interface that form no part of the claimed design.
